corporation

Application March 30, 1936, Serial No. 71,744

31 Claims. (Cl. 102—6)

This invention relates to new and useful improvements in indestructible release mechanism for blasting cartridges.

Several different kinds of blasting substances have been developed in the past for use in place of ordinary explosives for breaking down materials, such as coal. These substances are intended to be confined in indestructible cartridges or shells primarily for convenience in handling, uniformity in blasting effect which is due to charging the cartridges at a central station under expert supervision and controlling the direction of application of the blasting forces, etc. The charged cartridges or shells then are conveyed to the desired points of use and placed in drill holes formed in the material to be broken down. Representative examples of some of these different kinds of blasting substances or charges are as follows:

Carbon dioxide placed in the cartridge in liquid form and converted to the gaseous stage by the application of intense heat.

Combinations of solids and liquids; such as quick lime and water, which are maintained separated until the blasting operation is to be performed whereupon the elements are permitted to mix to form a gas.

Liquids which are capable of being quickly vaporized by the application of heat.

Gaseous charges which will increase in volume rapidly when subjected to intense heat, and

Purely chemical mixtures; for example, decomposable salts, which when heated will liberate a non-inflammable gas.

With all the aforementioned types of blasting substances or charges, a very rapid change of pressure occurs at the time of firing a cartridge charged with the same. Furthermore, the final pressure at which these charges are liberated is in most instances many times the pressure at which the charges are placed within the cartridges or shells. With some of these charges, the pressure at which the same is placed in a cartridge is comparatively high and will be raised above the initial charging pressure by a rise in the temperature of the surrounding atmosphere.

It will be appreciated that the confining of these charges in cartridges until the desired blasting pressure is obtained presents a difficult problem.

Carbon dioxide has been the only one of the aforementioned types of blasting charges or substances which, as far as applicant is aware, has gone into extensive commercial use. The problem of successfully confining a charge of liquid carbon dioxide in an indestructible cartridge or

shell is probably more difficult than with any of the other examples mentioned. This is due to the fact that the charge is placed within the cartridge at approximately a pressure of 1000 lbs. per square inch. The pressure of such a carbon dioxide charge will rise as high as 4000 lbs. per square inch when submitted to temperatures which are common in some localities during the summer months. When a carbon dioxide charge is heated for the purpose of converting it from a liquid to a gaseous stage, by the application of intense heat, the change takes place instantaneously. The pressures at which carbon dioxide charges have been released, in the commercial use of this type of blasting medium, have varied from 12,000 lbs. to 30,000 lbs., more or less, per square inch. It will not be difficult to understand, that to be able to maintain this type of blasting medium confined until a desired, predetermined blasting pressure is reached, and then suddenly liberate the charge cannot be accomplished with ordinary apparatus for controlling the flow of fluids at low pressures.

The method which has been most extensively adopted for effecting the desired control, in the commercial use of carbon dioxide as a blasting medium, consists of providing the indestructible cartridges or shells with rupturable wall portions. Specifically, the rupturable wall portion takes the form of a disk which is associated with a discharge cap in such a manner that the central portion will be sheared from the remainder of the disk when a predetermined blasting pressure is obtained.

The only disadvantage which results from the use of a rupturable disk form of discharge control is that a new disk must be used with each new charge and the application of a new disk to a cartridge necessitates disassembly of the aforementioned discharge cap to permit the insertion of the new disk and then reassembly of the discharge cap to retain the disk in place. The development of an indestructible mechanism which would permit of accurate control of the discharge pressure of blasting substances or charges of the above referred to characters, and particularly carbon dioxide would eliminate the cost of providing a new disk for each charge placed within a cartridge and would, of course, dispense with the necessity of disturbing the cartridge assembly to effect the substitution of a new disk.

It will be appreciated that with all of the types of blasting substances or charges above referred to, the interior of the chamber or chambers provided in the cartridges or shells for receiving

the blasting medium is not available for use as a housing means for the release mechanism. This is due to the fact that where a heater is needed to effect firing of the cartridge or where 5 the blasting medium takes the form of a solid, the chamber or chambers must be used for receiving these objects. The indestructible control mechanism, therefore, must be of a character which will permit it to be located entirely exteriorly of the portion of the cartridge intended for use to confine the blasting medium.

It is the primary object of this invention to provide indestructible discharge mechanism for blasting cartridges, intended to receive any of the 15 types of blasting charges above referred to, which will effectively and economically accomplish the desired control of the blasting charge so that blasting operations may be accomplished at any desired blasting pressures and with said pressures 20 under accurate control.

A further important object of the invention is to provide a form of indestructible discharge mechanism for blasting cartridges which will not occupy any portion of the chambers of the cartridges which are normally used for confining the blasting charges and their actuating devices.

A still further important object of the invention is to provide discharge mechanism for blasting cartridges which will not necessitate any portion 30 of the mechanism being replaced or adjusted after each firing operation.

Other objects and advantages of the invention will be apparent during the course of the following description.

35 In the accompanying drawings forming a part of this specification and in which like numerals are employed to designate like parts throughout the same,

Figure 1 is a longitudinal sectional view of a 40 fragmentary portion of a discharge cartridge with one form of indestructible discharge mechanism embodying this invention properly applied thereto.

Figure 2 is a transverse sectional view taken on 45 line 2—2 of Figure 1.

Figure 3 is a transverse sectional view taken on line 3—3 of Figure 1.

Figure 4 is a longitudinal sectional view of a 50 fragmentary portion of a blasting cartridge with a modified form of indestructible release mechanism operatively associated therewith.

Figure 5 is a similar view to Figure 4 but discloses the discharge mechanism in two different positions of operation.

55 Figure 6 is a transverse sectional view taken on line 6—6 of Figure 4.

Figure 7 is a longitudinal sectional view of a 60 fragmentary portion of a blasting cartridge with a further modified form of indestructible release mechanism embodying this invention operatively applied thereto, and

Figure 8 is a transverse sectional view taken on line 8—8 of Figure 7.

In the drawings, wherein for the purpose of 65 illustration are shown the preferred embodiments of this invention, reference character 10 in Figures 1, 4, 5 and 7 designates in its entirety a cartridge or shell which is adapted to have placed therein a substance or a combination of ingredients which, when properly acted upon, will develop a blasting medium at a desired work performing pressure. The same general type of cartridge is to be used with the three different modifications or forms of discharge mechanism 70 closed in these figures of the drawings. For a

complete disclosure of a cartridge of this character which is charged with carbon dioxide in liquid form, that is, gasified by the application of intense heat to produce the desired blasting energy, reference is hereby made to the patent issued to Dent Ferrell, et al., No. 1,805,541, issued May 19, 1931.

Referring specifically to the form of the invention illustrated in detail in Figures 1 to 3 inclusive, the discharge opening 11 of the cartridge 10 has threadedly connected thereto a tubular coupling member 12 which is provided with a plurality of obliquely arranged discharge ports 13 at a location intermediate its ends. Inwardly of the series of ports 13, the coupling member 12 is provided with a shoulder 14 which functions as a valve seat. On the opposite side of the ports 13, to the shoulder 14, the coupling is provided with a partition 15 which, as will be described at a later point, acts as a guide for a compound valve member and also as a seat for a valve portion of said member. Outwardly of the combined guide and seat forming partition 15, the coupling member 12 is bored out and internally screw-threaded at 16 for being threadedly connected to the reduced end 17 of a casing member 18. This casing member 18 is provided with a valve guide 19 which has formed therein a circular series of apertures 20. The casing member 18 is of tubular formation so as to provide a chamber 21. This chamber 21 is divided to a certain extent into two parts by the guide or partition 19 but these two parts are in constant communication with each other through the series of apertures 20. The outer end portion 22 of the casing member 18 is internally screw-threaded for receiving a plug 23 which functions to close the outer end of the chamber 20.

A packing ring or gasket 24 is provided to seal between the cartridge 10 and the coupling 12 to 40 prevent leakage through this threaded connection. The joint between the coupling 12 and the casing member 18 is packed or sealed by a cup leather 25 which is clamped in place by the ring 26 against one face of the partition 15. The adjacent end of the casing member 18 bears against the ring 26 to accomplish this clamping action. Packing rings or gaskets 27 and 28 are provided for sealing the joint between the closure plug 23 and the outer end of the casing member 18.

50 A compound valve device is provided and is designated in its entirety by the reference character 29. One end of this compound valve device is enlarged to form a valve head 30 adapted to engage the shoulder or seat 14. When this valve head 30 is seated on the shoulder 14, it functions to retain the blasting charge within the cartridge 10. The enlarged valve head 30 tapers rearwardly to blend into the stem portion 31. As shown in Figures 1 and 3, the rearwardly tapering portion 60 of the valve head 30 and the adjacent portion of the stem 31 are provided with a series of longitudinally extending grooves 32. It will be noted by inspecting Figure 1 that when the valve head 30 is arranged in engagement with the valve seat 14, the outer ends of the grooves 32 terminate at the partition 15. The stem of the compound valve device 29, outwardly of the ends of the grooves 32, cooperates with the partition 15 and cup leather 25 to form a valve device for closing 70 off communication between the chamber 21 and the bore of the coupling 12 which communicates with the discharge ports 13. When the valve head 30 is moved away from the valve seat 14, or into its dotted line position of Figure 1, the 75

series of longitudinally extending grooves 32 establish communication between the inner part of the chamber 21 and the bore of the coupling 12 which directly communicates with the discharge ports 13. It will be appreciated, therefore, that when the valve head 30 is unseated, the stem portion 31 of the compound valve device 29 will have been moved to a position where the grooves 32 will permit discharge of the contents of the chamber 21 through the discharge ports 13 along with the contents of the cartridge 10.

For the purpose of charging the chamber 21 with a fluid, such as air, under pressure, the closure plug 23 has formed therein a threaded aperture 33 which may be connected to a conduit leading from a suitable source of supply. To prevent discharge of the compressed fluid through the opening 33, a spring loaded check valve is provided for closing this opening. The ball check valve is retained in place by a cage 35 which is secured to the inner face of the closure plug 23 by means of the feet 36. These feet are intended to be suitably welded, or otherwise secured to the plug 23. For the purpose of initially closing both valve portions of the compound valve device 29, a spring 37 is provided. One end of this spring is received within a pocket 38 formed in the outer end of the valve device 29. The remaining end 30 of the spring is connected to the closure plug 23 by means of the feet 36 of the valve cage 35.

The operation of this device may be described as follows:

It will be noted that there is provided a unitary, self-contained mechanism which may be detachably connected to the discharge end of a blasting cartridge 10. With this unitary device properly connected to the cartridge, compressed air, or the like, is to be charged into the chamber 21. The pressure of this charge of air is to be such that it will retain the valve head 30 seated on the shoulder 14 against the pressure of the blasting charge within the cartridge 10 until the pressure of this blasting charge reaches the desired working pressure at which time the blasting charge is intended to overcome the pressure within the chamber 21. The charge of compressed air within the chamber 21 acts against the outer end of the valve stem 31 to maintain both valve portions of the device 29 seated or closed until the desired blasting pressure is attained within the cartridge.

After the chamber 21 is properly charged with compressed air, the cartridge 10 may be charged with the blasting medium. As stated above, this blasting medium may be of the form disclosed in the aforementioned Ferrell patent. The cartridge with its indestructible release mechanism is then ready to be transported to the location of a blasting operation and may be placed in a drill hole in the mine wall to be broken down. As is explained in the aforesaid Ferrell patent, the liquid carbon dioxide charge in the cartridge 10 is rapidly converted to a gas by means of a chemical heater unit which is electrically energized at the time the blasting operation is to be performed. The pressure of the charge within the cartridge 10 increases very rapidly and when the desired blasting pressure is attained, it will overcome the pressure of the charge of compressed air in the chamber 21 and will move the combined valve device 29 from its full line position of Figure 1 into its dotted line position of this disclosure. This movement of the valve device permits discharge of the blasting charge from the

cartridge 10 through the ports 13. The series of grooves 32 also establish communication between the compartment 21 and the discharge ports 13 with the result that the charge of highly compressed air is released from the chamber 21. The compressed air passes outwardly through the ports 13 with the blasting charge from the cartridge 10 and the compressed air, therefore, assists the blasting charge from the cartridge 10 in breaking down the material to be blasted. The release of the compressed air from the chamber 21 also removes from the compound valve device the force or energy which was employed to retain the two valve portions of this device in their closed positions.

Referring particularly to Figures 4, 5 and 6, wherein a modified form of indestructible discharge mechanism is illustrated, the character 40 designates a coupling member which is threadedly connected to the discharge end 11 of the cartridge 10. This coupling member 40 is provided, at a location intermediate its ends, with a series of obliquely arranged discharge ports 41. A threaded connection 42 is provided between the coupling 40 and the cartridge, as illustrated. Outwardly of the discharge ports 41, the coupling 40 is provided with a partition 43 which has formed therein a circular series of apertures 44. This partition 43 acts as a guide for the stem of a valve which will be referred to at a later point.

Threadedly connected at 45 to the coupling 40 is a casing member 46. This casing member has formed therein a partition 47 which is provided with a circular series of apertures 48. This partition 47 also acts as a guide for the stem of a valve device which will be referred to at a later point.

The outer end of the casing member 46 has threadedly connected thereto, as at 49, a closure plug 50. This plug has formed therein the angularly arranged, communicating passages 51 and 52. The outer end of the passageway 51 is closed by a threaded plug 53. The closure plug 50 has formed therein a recess 54 which is threaded to receive the plug 53. The wall of this recess 54 is provided with a series of longitudinally extending grooves which will permit fluid to be fed around the plug 53 when the latter is backed away from the position in which it closes the outer end of the passageway 51. By means of a suitable charging head, which is not illustrated as it forms no part of this invention, a suitable fluid under pressure, such as compressed air, may be fed through the passageway 51 and 52 of the closure plug 50 for charging the chamber 56 which is formed in the casing member 46. This chamber 56 is divided into two parts by the partition 47 but these parts are in constant communication with each other through the series of apertures 48.

For the purpose of sealing the joint between the coupling member 40 and the discharge end 11 of the cartridge 10, a suitable packing ring or gasket 57 is provided. The joint between the coupling member 40 and the casing member 46 is sealed by the packing ring or gasket 58. A packing ring or gasket 59 is provided for sealing the joint between the casing member 46 and the closure plug 50.

A compound valve device is provided in this modification for closing the discharge ends of the cartridge 10 and the chamber 56 in substantially the same manner as that described in connection with the form of the invention shown in Figures 1 to 3, inclusive. This compound valve de-

vice of Figures 4 and 5, however, differs structurally from the previously described valve device.

For the purpose of closing the discharge end of the cartridge 10, a valve head 60 is provided 5 and is adapted to seat against the extremity 61 of the end 11 of the cartridge 10. A valve stem 62, jointed at 63, is provided for the valve head 60. This valve stem 62 is guided by the partition 43 and terminates at its outer end in a piston-like 10 enlargement 64 which is located in the chamber 58.

A second valve head 65 is provided and functions to control the release of the compressed air from the chamber 56. This valve head 65 seats 15 against the extremity 66 of the outer end portion of the coupling 40. A tubular stem 67 is provided for the valve head 65. The bore of this tubular stem 67 slidably receives the stem 62 of the valve head 60.

20 The outer end of the tubular valve stem 67 has a tapered threaded connection 68 with a sleeve 69. A tapered threaded connection 70 is provided between the outer end of this sleeve 69 and a cap 70. This cap is provided with a centrally apertured end wall 71, as clearly illustrated.

A diaphragm in the form of a rubber disk 72 is clamped between the outer end of the sleeve 69 and the end wall 71 of the cap 70. For the 30 purpose of obtaining a tight clamping connection between this diaphragm and the sleeve 69 and cap 70, the margin of this diaphragm is faced on opposite sides with the metal rings 73. These metal rings are intended to be surface bonded, as 35 by vulcanization, to the margin of the diaphragm.

It will be seen that the outer end of the tubular valve stem 67, the sleeve 69, the cap 70 and the diaphragm 72 form a chamber for receiving the enlarged piston-like head 64 of the valve stem 40 62. A lost motion connection between the valve stem 67 and the valve stem 62 is provided by this structure.

The mode of operation of this form of the invention will be described as follows:

45 Prior to charging the cartridge 10 with the blasting medium to be employed, a suitable charge of compressed air is fed to the chamber 56. The pressure of this compressed air charge should be such that it will retain the two valve devices seated until the pressure of the blasting charge within the cartridge 10 reaches a desired working 50 pressure at which time the blasting charge will overcome the pressure of the compressed air charge within the chamber 56 for opening the two valves. The charge of compressed air fed to the chamber 56 functions to seat the valve 65 for preventing leakage of this compressed air from the chamber. The compressed air also applies pressure to the outer face of the piston-like 55 head 65 of the valve stem 62. This application of force to the piston-like head 64 takes place through the rubber diaphragm 72 and deflects or stretches this diaphragm, as shown in Figure 5, to take up a portion of the lost motion connection between the stems of the two valves. The application of force to the piston-like head 64 moves the valve head 60 against its seat to close the discharge end of the cartridge 10. The indestructible release mechanism of this form of the 60 invention is now in readiness for the cartridge 10 to be charged with its blasting medium. As explained above, this blasting medium may be of the type fully disclosed and described in the aforementioned Ferrell patent. When the blasting charge in the cartridge 10 has been acted

upon to raise the pressure of the same to a desired blasting pressure, the pressure of the charge will function to overcome the pressure of compressed air within the chamber 56. The valve 60 will be moved from its seat against extremity 5 61 of the cartridge. This outward movement of the valve head 60 and its rigid stem 62 causes the piston-like head 64, of the stem 62 to move outwardly and take up the lost motion connection between it and the valve stem 67. The diaphragm 72 will be straightened out, as shown in Figure 4, and the piston-like head 64 will apply force against the end wall 71 of the cap 70 through the medium of the diaphragm 72. It will be noted that the aperture formed in this 15 end wall 71 is of less diameter than the diameter of the piston-like head 64 so that this end wall 71 of the cap 70 will back up or reinforce the diaphragm 72 against the pressure of the piston-like head 64. 20

After this lost motion connection is taken up between the two valve stems, the pressure of the blasting charge within the cartridge 10 will move the valve head 65 away from its seat 66 for releasing the charge of compressed air from the 25 chamber 56. This charge of compressed air will pass outwardly through the discharge ports 41 along with the blasting charge from the cartridge 10. Figure 5 discloses the two valves 60 and 65 in their closed positions in full lines and in their 30 opened positions in dotted lines.

In the form of the invention disclosed in Figures 7 and 8, the blasting cartridge 10 has its discharge end 74 threadedly connected to one end of a coupling member 75. The remaining end 76 35 of this coupling member is threadedly connected to a casing member 77. A series of obliquely arranged discharge ports 78 are provided in the coupling member 75 at a point intermediate its ends. 40

The outer end of the casing member 77 is threadedly connected at 79 to a plug 80 which functions to close the end of the casing member. Passageways 81 and 82 are provided in the closure plug 80. The extremity of the passageway 82 45 is provided with a closure 83 which is threadedly connected to the plug 80 and cooperates with grooves 84 for permitting compressed air, or the like, to be fed into the chamber 85 formed in the casing member 77, in the manner described in 50 connection with the form of the invention illustrated in Figure 4.

A packing or gasket 86 is provided for sealing the connection between the cartridge 10 and the coupling member 75. A packing ring or gasket 55 87 is provided for sealing the connection between the casing member 77 and the closure plug 80.

A compound valve device, designated in its entirety by the reference character 88, consists of 60 a valve head 89 which is adapted to seat against the extremity 90 of the discharge end 74 of the cartridge 10. This valve head 89 is rigidly connected by the stem 91 to a second valve head 92 65 which is adapted to seat against a shoulder 93, preferably formed integrally with the inner wall of the casing member 77. It will be noted that the periphery of the valve head 89 is provided with a series of axially extending grooves 94. The periphery of the valve head 92 also is provided with a series of axially extending grooves 95. Figure 8 discloses the grooves 95 in the periphery of the valve head 92. It is to be understood that the grooves 94 in the valve head 89 70

60

65

70

75

75

will have the same appearance when viewed from the outer end of said head.

It will be appreciated that the chamber 85 of the casing member 77 is to be charged with a compressed fluid, such as air and that the pressure of this compressed air will bear against the inner face of the valve head 92 for forcing this valve head to seat against the shoulder 93 for confining the charge of compressed air within the 10 chamber. This seating movement of the valve head 92 is to be employed for seating the valve head 89 against its seat 90 for the purpose of confining the blasting charge within the cartridge 10 until the pressure of this charge reaches a pre- 15 determined value with respect to the pressure of the charge within the chamber 85. When this pressure ratio is reached, the blasting charge in the cartridge 10 will overcome the charge of compressed air in the chamber 85 for moving 20 both valves off of their seats. The unseating of these two valves will permit the blasting charge from the cartridge 10 to be released through the discharge ports 78. The grooves 94 and 95 formed in the peripheries of the valve heads 89 and 92 25 will permit the charge of compressed air to be released from the chamber 85 for passage through the ports 78.

It will be appreciated that when produced in quantities, it will be impossible, due to normal 30 manufacturing tolerances, to have both valve heads simultaneously engage their respective seats with uniform sealing effects unless some adjustment is permitted. Adjustment between the two valve heads is not plausible because these heads 35 are normally inaccessibly located within the coupling and housing members. In this structure, the desired adjustment, therefore, is to be brought about between the two valve seats. The coupling member 75 is intended to be connected to the 40 discharge end 74 of the cartridge in a non-adjustable manner. That is, the valve seat 90, formed by the cartridge 10, is intended to be fixed relative to the coupling member 75. The valve seat 93 for the valve head 92 is intended to be fixed 45 relative to the casing member 77. By accomplishing an adjustment between the coupling member 75 and the casing member 77, the desired adjustment between the two valve seats may be accomplished. For that reason, clearance, as at 50 96, is provided between the opposed faces 97 and 98 of the casing member 77 and coupling member 75 respectively. This clearance will permit of relative adjustment between the members 75 and 77. A locking nut or ring 99 is provided for retaining the coupling and casing members in their 55 desired adjusted positions.

To determine the adjustments necessary between the coupling and casing members, the chamber 85 may be charged with compressed air, or the like, at a time when the coupling member 75 and its cartridge 10 are backed away from the casing member 77. The valve head 92, therefore, will be permitted to properly engage its seat 93. The cartridge 10 with the coupling member 75 60 then may be moved or adjusted toward the casing member 77 until the valve head 89 tightly engages its seat 90. To determine whether the valve head 89 is tightly and completely engaging its seat 90, the cartridge 10 may be preliminarily charged with a compressible fluid, such as air. After the proper adjustment has been made, the lock nut 99 may be tightened against the surface 97 of the casing member 77 for maintaining this 65 adjustment. The mechanism then will be ready

for repeated use without further adjustment being necessary.

It will be appreciated that with the three forms of indestructible release devices, the same general principles are involved. These consist of the provision of a compound valve device which will function to retain a blasting charge within a cartridge and a valve controlling charge of a compressible fluid within an auxiliary chamber. When the pressure of the blasting charge within 10 the cartridge reaches a predetermined value with respect to the pressure of the charge within the auxiliary chamber, the compound valve device will be operated for releasing the charges from both the cartridge and the auxiliary chamber. 15 The control mechanism of each of these modifications is of such a character that it will not occupy any of the space formed in the blasting cartridge. This is very desirable because it leaves the entire interior of the blasting cartridge available for occupancy by the blasting medium and its associated mechanism. It further will be appreciated that these release devices operate on the principle of employing the pressure of fluid medium in an auxiliary chamber for counter- 20 acting the pressure of a fluid medium in the blasting chamber until the pressure of said latter fluid medium overcomes the pressure of the fluid medium in the auxiliary or control chamber. 25

It is to be understood that the forms of this 30 invention herewith shown and described are to be taken as preferred examples of the same, and that various changes in the shape, size, and arrangement of parts may be resorted to without departing from the spirit of the invention or the scope 35 of the subjoined claims.

Having thus described the invention, I claim:

1. In combination, a cartridge having a chamber formed with a discharge opening and adapted to receive a blasting charge the pressure of which 40 is suddenly elevated to the desired blasting pressure at the time of releasing the charge, a valve for controlling the release of the blasting charge through said opening, and fluid pressure actuated means located on the opposite side of the discharge opening from said chamber for retaining said valve closed until the desired blasting pressure has been reached in the chamber, said means including an auxiliary fluid pressure chamber, and a plunger in said chamber subjected to the 45 pressure of the fluid and connected to said valve. 50

2. In combination, a cartridge having a chamber formed with a discharge opening and adapted to receive a blasting charge the pressure of which is suddenly elevated to the desired blasting pres- 55 sure at the time of releasing the charge, a valve for controlling release of the blasting charge through said opening and movable in the direction of flow of the released blasting charge during opening movement, and means operated by 60 the pressure of an independent fluid charge for opposing opening movement of the valve until the pressure of the blasting charge overcomes the pressure of said fluid charge, said means including discharge mechanism for the independent 65 fluid charge.

3. In combination, a cartridge having a chamber formed with a discharge opening and adapted to receive a blasting charge the pressure of which is suddenly elevated to the desired blasting pres- 70 sure at the time of releasing the charge, a valve for controlling release of the blasting charge through said opening, and means operated by the pressure of an independent fluid charge for op- 75 posing opening movement of said valve until the

pressure of the blasting charge overcomes the pressure of said fluid charge, said means including discharge mechanism for the independent fluid charge effecting release of said latter charge 5 through said discharge opening for the chamber.

4. In combination, a cartridge having a chamber formed with a discharge opening and adapted to receive a blasting charge the pressure of which is suddenly elevated to the desired blasting pressure at the time of releasing the charge, a valve for controlling release of the blasting charge through said opening, means operated by the pressure of an independent fluid charge for opposing opening movement of said valve until 10 the pressure of the blasting charge overcomes the pressure of said fluid charge, and means for releasing the independent fluid charge through said discharge opening at the time of releasing the blasting charge.

20 5. In combination, a cartridge having a chamber formed with a discharge opening and adapted to receive a blasting charge the pressure of which is suddenly elevated to the desired blasting pressure at the time of releasing the charge, 25 a valve for controlling release of the blasting charge through said opening and movable in the direction of flow of the released blasting charge during opening movement, means operated by the pressure of an independent fluid charge for opposing opening movement of the valve until the pressure of the blasting charge 30 overcomes the pressure of said fluid charge, and valve means actuated by opening movement of the first valve for releasing the independent fluid charge at the time of releasing the blasting charge.

40 6. In combination, a cartridge having a chamber formed with a discharge opening and adapted to receive a blasting charge the pressure of which is suddenly elevated to the desired blasting pressure at the time of releasing the charge, an auxiliary chamber having a discharge opening and adapted to receive a fluid charge under pressure, a valve device for controlling release of 45 the blasting charge from the cartridge chamber and the fluid charge from the auxiliary chamber, and means subject to the fluid charge in the auxiliary chamber for actuating said valve device to retain both of said charges confined in their 50 respective chambers until the pressure of the blasting charge reaches a predetermined value relative to the pressure of the fluid charge, whereupon the blasting charge will actuate the valve device for releasing both charges.

55 7. In combination, a cartridge having a chamber formed with a discharge opening and adapted to receive a blasting charge the pressure of which is suddenly elevated to the desired blasting pressure at the time of releasing the charge, an auxiliary chamber having a discharge opening and adapted to receive a fluid charge under pressure, means comprising a valve for each of said 60 discharge openings for controlling release of the charges from both chambers, and means subject to the fluid charge in the auxiliary chamber for actuating said valve means to retain both of said charges confined in their respective chambers until the pressure of the blasting charge reaches a predetermined value relative to the pressure 65 of the fluid charge, whereupon the blasting charge will actuate said valve means for releasing both charges.

70 8. In combination, a cartridge having a chamber formed with a discharge opening and adapted 75 to receive a blasting charge the pressure of which

is suddenly elevated to the desired blasting pressure at the time of releasing the charge, an auxiliary chamber having a discharge opening and adapted to receive a fluid charge under pressure, coupling means for connecting said chambers and having a series of radial discharge ports, a valve device for controlling release of the blasting charge from the cartridge chamber into said coupling means and the fluid charge from the auxiliary chamber into said coupling means, and means subject to the fluid charge in the auxiliary chamber for controlling said valve device to retain both of said charges confined in their respective chambers until the pressure of the blasting charge reaches a predetermined value 15 relative to the pressure of the fluid charge, whereupon the blasting charge will actuate the valve device for releasing both charges into said coupling means for simultaneous discharge through said ports.

20 9. In combination, a cartridge having a chamber formed with a discharge opening and adapted to receive a blasting charge the pressure of which is suddenly elevated to the desired blasting pressure at the time of releasing the charge, and a 25 self-contained, unitary control device adapted to be located outwardly of and detachably connected to said cartridge adjacent said discharge opening for controlling release of the blasting charge from said chamber, said means including dual 30 valve mechanism.

35 10. In combination, a cartridge having a chamber formed with a discharge opening and adapted to receive a blasting charge the pressure of which is suddenly elevated to the desired blasting pressure at the time of releasing the charge, and a self-contained fluid pressure operated unitary control device adapted to be detachably connected to said cartridge and positioned entirely outside said chamber for controlling release of 40 the blasting charge from said chamber, said means including a compound valve device.

45 11. A self-contained unitary control device adapted to be detachably coupled to the discharge end of a blasting cartridge to effect release of the cartridge charge, comprising a valve for retaining the blasting charge in the cartridge and movable away from the cartridge in opening, a chamber for receiving and confining a fluid charge under pressure and means 50 in said chamber subject to the pressure of the fluid charge for retaining said valve closed until the pressure of the blasting charge reaches a desired value relative to the pressure of the fluid charge.

55 12. A self-contained unitary control device adapted to be detachably coupled to and positioned entirely outside one end of a blasting cartridge to effect release of the cartridge charge, comprising a valve for retaining the blasting 60 charge in the cartridge, a chamber for receiving a fluid charge under pressure, means in said chamber subject to the pressure of the fluid charge for retaining said valve closed until the pressure of the blasting charge reaches a desired value relative to the pressure of the fluid charge, and means for releasing the charge of fluid from said chamber when the valve is operated to release the blasting charge from the cartridge.

65 13. A self-contained unitary control device adapted to be detachably coupled to a blasting cartridge to effect release of the cartridge charge, comprising a valve for retaining the blasting charge in the cartridge, a chamber for receiving a 70

fluid charge under pressure and chargeable prior to coupling the device to a cartridge, means in said chamber subject to the pressure of the fluid charge for retaining said valve closed until the 5 pressure of the blasting charge reaches a desired value relative to the pressure of the fluid charge, and a second valve for releasing the charge of fluid from said chamber when the first valve is opened to release the blasting charge.

10 14. In combination, a cartridge having a chamber formed with a discharge opening and adapted to receive a blasting charge, the pressure of which is suddenly elevated to the desired blasting pressure at the time of releasing the charge, means for 15 controlling release of the blasting charge through said opening, means operated by the pressure of an independent fluid charge for opposing charge release operation of the first mentioned means until the pressure of the blasting charge over- 20 comes the pressure of said fluid charge, and means for releasing the independent fluid charge at the time of operation of the blasting charge release, said two release means being capable of independent opening and closing movements.

25 15. In combination, a cartridge having a chamber formed with a discharge opening and adapted to receive a blasting charge, the pressure of which is suddenly elevated to the desired blasting pressure at the time of releasing the charge, means for 30 controlling release of the blasting charge through said opening, means operated by the pressure of an independent fluid charge for opposing charge release operation of the first mentioned means until the pressure of the blasting charge overcomes the pressure of said fluid charge, and means actuated by the charge release operation of the first mentioned means for 35 releasing the independent fluid charge.

16. In combination, a cartridge having a chamber 40 formed with a discharge opening and adapted to receive a blasting charge, the pressure of which is suddenly elevated to the desired blasting pressure at the time of releasing the charge, means for controlling release of the blasting 45 charge through said opening, means operated by the pressure of an independent fluid charge for opposing charge release operation of the first mentioned means until the pressure of the blasting charge overcomes the pressure of said fluid charge, and valve means for releasing the independent fluid charge as a result of operation of 50 the blasting charge release means.

17. In combination, a cartridge having a chamber 55 formed with a discharge opening and adapted to receive a blasting charge, the pressure of which is suddenly elevated to the desired blasting pressure at the time of releasing the charge, a valve for controlling release of the blasting charge through said opening and movable in the 60 direction of flow of the released blasting charge during opening movement, means operated by the pressure of an independent fluid charge for opposing opening movement of the valve until the pressure of the blasting charge overcomes the pressure of said fluid charge, and means actuated by opening movement of the valve for releasing the independent fluid charge at the time of releasing the blasting charge.

18. In combination, a cartridge having a chamber 70 formed with a discharge opening and adapted to receive a blasting charge, the pressure of which is suddenly elevated to the desired blasting pressure at the time of releasing the charge, means for controlling release of the blasting charge through said opening, means operated by

the pressure of an independent fluid charge for opposing charge release operation of the first mentioned means until the pressure of the blasting charge overcomes the pressure of said fluid charge, and valve means for releasing the independent fluid charge through said chamber discharge opening at the time of operation of the blasting charge release means. 5

19. In combination, a cartridge having a chamber formed with a discharge opening and adapted to receive a blasting charge, the pressure of which is suddenly elevated to the desired blasting pressure at the time of releasing the charge, an auxiliary chamber having a discharge opening and adapted to receive a fluid charge under pressure, means for controlling release of the blasting charge from the cartridge chamber and the fluid charge from the auxiliary chamber, and means subject to the fluid charge in the auxiliary chamber for actuating said means to retain both 20 of the charges confined in their respective chambers until the pressure of the blasting charge reaches a predetermined value relative to the pressure of the fluid charge, whereby the blasting charge will actuate the first mentioned means 25 for releasing both charges.

20. A self-contained unitary control device adapted to be detachably coupled to and positioned exteriorly of the discharge end of a blasting charge receiving chamber for a blasting 30 cartridge to effect release of the cartridge charge, comprising release means for the blasting charge in the cartridge, a chamber for receiving a fluid charge under pressure, means in said chamber subject to the pressure of the fluid charge for 35 restraining operation of said release means until the pressure of the blasting charge reaches a desired value relative to the pressure of the fluid charge, and means for releasing the charge of fluid from said chamber when the blasting charge 40 release means is operated to release the blasting charge.

21. In combination, a cartridge having a chamber formed with a discharge opening and adapted to receive a blasting charge, the pressure of which 45 is elevated to the desired blasting pressure to effect release of the charge, an auxiliary chamber having a discharge opening and adapted to receive a fluid charge under pressure, a compound valve device for controlling release of the charges 50 from said chambers through their respective discharge openings, said compound valve device including lateral discharge ports common to both of said chambers for releasing to the atmosphere the charges released through said discharge 55 openings, and means operatively connected to said valve device and subject to the fluid charge in the auxiliary chamber for actuating said valve device to release the charges from both chambers when the blasting charge reaches the desired 60 blasting pressure.

22. In combination, a cartridge having a chamber formed with a discharge opening and adapted to receive a blasting charge, the pressure of which is elevated to the desired blasting pressure to effect release of the charge, an auxiliary chamber having a discharge opening and adapted to receive a fluid charge under pressure, a valve seat associated with each discharge opening, a coupling for connecting said chambers and having lateral discharge ports located between said valve seats, a compound valve device including a valve for each of said seats for controlling release of the charges from both of said chambers into said coupling, and means subject to the 75

- pressures of the charges in both of said chambers for actuating said valve device to release said charges when said pressures bear a predetermined relation one to the other.
5. 23. In combination, a cartridge having a chamber formed with a discharge opening and adapted to receive a blasting charge, the pressure of which is elevated to the desired blasting pressure to effect release of the charge, an auxiliary chamber having a discharge opening and adapted to receive a fluid charge under pressure, a valve seat associated with each discharge opening, a compound valve device including a valve for each of said seats for controlling release of the charges from both of said chambers, means for effecting uniform engagement of both of said valves against their seats by limited movement of said valves relative to each other, and means subject to the pressures of the charges in both 10 said chambers for actuating said valve device to release said charges when said pressures bear a predetermined relation one to the other.
24. In combination, a cartridge having a chamber formed with a discharge opening and adapted to receive a blasting charge, the pressure of which is elevated to the desired blasting pressure to effect release of the charge, an auxiliary chamber having a discharge opening and adapted to receive a fluid charge under pressure, a valve seat associated with each discharge opening, a compound valve device including a valve for each of said seats for controlling release of the charges from both of said chambers, means for effecting automatic axial adjustment between the valves during seating movement for causing a uniform seating engagement, and means subject to the pressures of the charges in both of said chambers for actuating said valve device to release said charges when said pressures bear a predetermined relation one to the other.
25. In combination, a cartridge having a chamber formed with a discharge opening and adapted to receive a blasting charge, the pressure of which is elevated to the desired blasting pressure to effect release of the charge, an auxiliary chamber having a discharge opening and adapted to receive a fluid charge under pressure, a valve seat associated with each discharge opening, a compound valve device including a valve for each of said seats for controlling release of the charges from both of said chambers, means for effecting adjustment between said valve seats for causing uniform seating engagement of said valves, and means subject to the pressures of the charges in both of said chambers for actuating said valve device to release said charges when said pressures bear a predetermined relation one to the other.
26. In combination, a cartridge having a chamber formed with a discharge opening and adapted to receive a blasting charge, the pressure of which is elevated to the desired blasting pressure to effect release of the charge, an auxiliary chamber having a discharge opening and adapted to receive a fluid charge under pressure, a valve seat associated with each discharge opening, a compound valve device including a valve for each
- of said seats for controlling release of the charges from both of said chambers, a lost motion connection between the valves of said device for effecting uniform engagement of the valves against their seats, and means subject to the pressures of the charges in both of said chambers for actuating said valve device to release said charges when said pressures bear a predetermined relation one to the other.
27. In combination, a blasting cartridge having a plurality of ports through which the contents of the cartridge are to be discharged into the material to be broken down, said cartridge having a blasting charge receiving chamber and a control chamber to receive a fluid charge under pressure, and means for effecting simultaneous discharge of the blasting charge and the fluid charge through all of said ports when the pressures of the charges in said chambers reach a predetermined value relative to each other.
28. In combination, a blasting cartridge having a plurality of ports through which the contents of the cartridge are to be discharged into the material to be broken down, said cartridge having a blasting charge receiving chamber and a control chamber to receive a fluid charge under pressure, and differential fluid pressure valve means for effecting simultaneous discharge of the blasting charge and fluid charge through all of said ports when the pressures of the charges in said chambers reach a predetermined value relative to each other.
29. In combination, a pair of chambers adapted to receive fluid charges under pressure, a valve seat for each chamber, a valve device including rigidly connected valves for both of said seats, said valves being operated for opening and closing movements by the differences in pressures in said chambers, and means for adjusting said valve seats relative to each other to effect uniform engagement of said valves with their seats.
30. In combination, a pair of chambers adapted to receive fluid charges under pressure, a valve seat for each chamber, a compound valve device including a valve for each valve seat, said valves each being subject to the fluid pressure in its respective chamber, a limited slidable connection between said valves to permit uniform seat engagement and to transmit the pressure applied to each valve from its chamber to the valve of the other chamber, and means for sealing said slidable connection against leakage of said fluid from one chamber to the other.
31. In combination, a pair of chambers adapted to receive fluid charges under pressure, a valve seat for each chamber, a compound valve device including a valve for each valve seat, said valves each being subjected to the fluid pressure in its respective chamber, a limited slidable connection between said valves, and means subjected to the pressures of the charges in both of said chambers for operatively connecting said valves to effect opening and closing movements of both valves in response to differences in pressure between said chambers.

LEONARD D. MYERS.
